assignors to General Mower Corporation, Buffalo,
N.Y., a corporation of New York

Application March 31, 1958, Serial No. 50,248

Term of patent 7 years

(Cl. D40—1)

Fig. 1 is a perspective view of a combined sulky and power lawn mower embodying our new design, this view being taken from the front and to the left thereof.

Fig. 2 is an elevational view of the front end thereof.

Fig. 3 is a side elevational view thereof, viewed from the left of the sulky as shown in Fig. 2.

Fig. 4 is a top plan view thereof.

The essential features of our design reside in the portions shown in full lines.

We claim:

The ornamental design for a combined sulky and power lawn mower, substantially as shown and described.
